DESIGN FOR A DISPENSING CONTAINER TOP

Ellis M. Houghton, Marion, Ohio, assignor to Double Duty Products, Inc., Cleveland, Ohio, a corporation of Ohio

Application July 5, 1941, Serial No. 101,923

Term of patent 14 years

To all whom it may concern:

Be it known that I, Ellis M. Houghton, a citizen of the United States and a resident of Marion, in the county of Marion and State of Ohio, have invented a new, original, and ornamental Design for a Dispensing Container Top, of which the following is a specification, reference being had to the accompanying drawing, forming a part thereof.

In said drawing, Fig. 1 is a side view of a dispensing container top showing my new design; Fig. 2 is a similar view of said container top, the container top being turned 90° from its Fig. 1 position; and Fig. 3 is a top plan view of said container top.

I claim:

The ornamental design for a dispensing container top, substantially as shown.

ELLIS M. HOUGHTON.
